(57) **CLAIM**

We claim the ornamental design for the pepper corer, as shown.

DESCRIPTION

FIG. 1 is a perspective view of a pepper corer, showing our new design;

FIG. 2 is a front view of the pepper corer, the back view being a minor image;

FIG. 3 is a top view of the pepper corer;

FIG. 4 is a left side view of the pepper corer, the right side view being a mirror image; and,

FIG. 5 is a bottom view of the pepper corer.
